(57) **CLAIM**

The ornamental design for a cap for a cosmetic container, substantially as shown.

DESCRIPTION

FIG. 1 is a top, front, right side, perspective view of our new design for a cap for a cosmetic container;

FIG. 2 is a right side elevational view of the cap for a cosmetic container shown in FIG. 1;

FIG. 3 is a front elevational view of the cap for a cosmetic container shown in FIG. 1;

FIG. 4 is a left side elevational view of the cap for a cosmetic container shown in FIG. 1;

FIG. 5 is a rear elevational view of the cap for a cosmetic container shown in FIG. 1;

FIG. 6 is a top plan view of the cap for a cosmetic container shown in FIG. 1; and,

FIG. 7 is a bottom plan view of the cap for a cosmetic container shown in FIG. 1.

The broken lines and the area within the broken lines shown in FIG. 7 form no part of the claimed design.

1 Claim, 2 Drawing Sheets
